(57) **CLAIM**

The ornamental design for a clip, as shown and described.

DESCRIPTION

FIG. 1 is a perspective view of a first embodiment of a clip showing my new design;

FIG. 2 is a front view, the opposite side being identical, thereof;

FIG. 3 is a top view thereof;

FIG. 4 is a left side thereof;

FIG. 5 is a right side view thereof;

FIG. 6 is a perspective view of a second embodiment of a clip showing my new design;

FIG. 7 is a front view thereof, the rear view being a mirror image thereof;

FIG. 8 is a top view thereof;

FIG. 9 is a left side view thereof; and,

FIG. 10 is a right side view thereof.

In FIGS. 6-10 the areas including various degrees of stipple shading indicate different hues of color.

In FIGS. 6-10 the dash lines used are shown for illustrative purposes only to delineate color change and are no part of the claimed design.
